UNITED STATES PATENT OFFICE.

RALPH E. SMITH, ROY J. ARNOLD, AND JOHN C. GAY, OF GALION, OHIO, ASSIGNORS
TO THE GALION METALLIC VAULT COMPANY, OF GALION, OHIO, A CORPORATION OF
OHIO.

FASTENING DEVICE.

Application filed July 31, 1925. Serial No. 47,196.

Our invention relates to fastening devices and in particular to a fastening device for a grave vault.

The object of our invention is to provide 5 a fastening mechanism for grave vaults, but which can be used for other purposes, so arranged to easily fasten and unfasten from the outside of the vault, to form a permanent seal of the vault.

10 It is also our object to provide a mechanism which will stiffen the upper part of the sides of the vault.

It is a further object of our invention to provide a novel form of cover and side walls 15 for a vault or container, either singly or in combination with our novel form of fastening mechanism.

Referring to the drawings:

Figure 1 is a side elevation of a portion 20 of the vault showing the exterior appearance of the vault with the fastening mechanism in place;

Figure 2 is a section on the line 2—2 of Figure 1;

25 Figure 3 is a section on the line 3—3 of Figure 2 fastening at the bottom of the locking mechanism;

Figure 4 is a perspective of the fastening member turned upside down to illustrate its 30 construction;

Figure 5 is an end elevation of the vault.

Referring to the drawings, in detail, 1 is the bottom of the grave vault, having sides 2, ends 3 and a cover 4. This cover has an 35 overhanging flange 5 which depends downwardly over the extended ledge of the case, the case being the body of the vault, composed of the ends, bottom and side walls. The side walls of the case are extended outwardly at 6, then upwardly at 7, parallel 40 to the wall 5 of the cover, inwardly at 8, parallel to the cover 4, but spaced therefrom, there being between the cover and this 45 inwardly extending portion 8, a rubber gasket 9. For strengthening purposes, the wall of the case is turned inwardly and outwardly beneath the wall 8, as at 10. A space 11 is formed in this outwardly extended portion of the case composed of members 6, 7, 50 8 and 10. It is within this space that the fastening member 12 is projected when the case and cover are secured together.

This fastening member is carried between spaced tracks 13 having sides 14 engaged with the sides 15 of the fastening member 12 to guide the fastening member in its reciprocal movement. The fastening member is provided with upwardly extending shoulders 16 and 17. The shoulders are engaged by the rotating member or actuating finger 18 which engages therewith. The engagement of the finger 18 with the shoulders 17 serves to move the fastening member inwardly or outwardly, and the engagement of the other end of the finger 18 with the shoulders 16 serves to limit the inward or outward movement of the fastening member 12 and the rotation of the actuating finger 18. This actuating finger is centered and pivoted upon a bolt 19 which passes 65 through a slot 20 in the fastening member 12. This is carried by the cover 4 and is provided with a bolt head 21, beneath which is a copper washer 22 resting on top of the cover 4. Beneath the cover is a rubber washer 23 and beneath the rubber washer 23 is a steel washer 24 supported on the upper sides of the plate 12 in the guides 14. The lower end of the bolt is provided with a nut 25 welded thereon. 70

Thus, when the bolt is rotated, the finger 18 will be actuated and the fastening member pushed into the space 11 under the plate 10 or removed therefrom, thus fastening or unfastening the cover on the case. 75

The fastening member is provided with an upwardly extending flange 26 at the rear thereof. It will be noted that the limiting shoulders 17 are spaced backwardly from the end of the fastening member 12 to permit the fastening to take place without the shoulder 17 engaging with the wall 2 of the case. 80

It will be noted that the nut 25 is shown in the drawing below and separated from the finger 18. The bolt 19 is threaded through the finger 18. It is thus possible not only to actuate the finger 18 but by turning the bolt to draw the cover down tightly against the case, compressing the resilient 95 members and making an air-tight and water-tight seal.

It will be understood that we desire to comprehend within our invention such

modifications as may be necessary to adapt it to varying conditions and uses. We comprehend this application to various forms of containers and its use as a locking mechanism under varying conditions.

Having thus fully described our invention, what we claim as new and desire to secure by Letters Patent, is:—

1. In combination, a case, a cover, means to support a fastening member carried on said cover, a fastening member slidably mounted thereon, and means carried by said cover for moving said member into and out of engagement with said case to fasten the cover thereon, said means for receiving said fastening member on the case consisting of the wall of the case turned over to form a receiving and engaging portion of the case, said fastening member being adapted to engage the under portion of that portion of the case, and the cover being adapted to engage the upper portion, and resilient sealing means between said cover and said case.
2. In combination, a case having its upper edges formed into laterally disposed U-shaped portions, a fastening member to be inserted therein, a cover adapted to be mounted thereon, means to slidably guide said fastening member, means to actuate said locking finger inwardly and outwardly, said actuating means consisting of a bolt suspended from said cover, an arm on said bolt and shoulders on said fastening member, adapted to be engaged by said arm.
3. In combination, a case having an outwardly, upwardly and inwardly extending portion along the upper margin thereof, a cover adapted to be mounted thereon, a sliding bolt adapted to be inserted in the space formed by the outwardly, upwardly and inwardly extending portion of the case, means on said bolt to guide it in a guideway, a guideway, a rotatable bolt suspended from said cover between said guideway and through said bolt shoulders on said sliding bolt, an arm carried by said rotating bolt adapted to be engaged to said shoulders whereby when the rotatable bolt is rotated the sliding bolt will be moved into and out of engagement with the case.
4. In combination, a case having an outwardly, upwardly and inwardly extending portion along the upper margin thereof, a cover adapted to be mounted thereon, a sliding bolt adapted to be inserted in the space formed by the outwardly, upwardly and inwardly extending portion of the case, means on said bolt to guide it in a guideway, a guideway, a rotatable bolt suspended from said cover between said guideway and through said bolt shoulders on said sliding bolt, an arm carried by said rotating bolt adapted to be engaged to said shoulders whereby when the rotatable bolt is rotated the sliding bolt will be moved into and out

of engagement with the case, and yielding means between said upper portion of the case and said under portion of the cover where they are adjacent.

5. In combination, a case having an outwardly, upwardly and inwardly extending portion along the upper margin thereof, a cover adapted to be mounted thereon, a sliding bolt adapted to be inserted in the space formed by the outwardly, upwardly and inwardly extending portion of the case, means on said bolt to guide it in a guideway, a guideway, a rotatable bolt suspended from said cover between said guideway and through said bolt shoulders on said sliding bolt, an arm carried by said rotating bolt adapted to be engaged to said shoulders whereby when the rotatable bolt is rotated, the sliding bolt will be moved into and out of engagement with the case, and yielding means between said upper portion of the case and said under portion of the cover, where they are adjacent, and a depending marginal flange depending from the cover on the outside to the outwardly projecting portion of the case.

6. In combination, a case having a marginal U-shaped slot along the top thereof formed by an outwardly bent portion of the casing wall, a reciprocatory member adapted to be moved into and out of said slot to fasten a cover to the case, a cover, means on said cover consisting of a bolt to support said member and actuate it, an arm carried by said bolt adapted to engage with shoulders on said reciprocatory member for the actuation thereof, said bolt passing through a slot in said reciprocatory member.

7. In combination, a case having a marginal U-shaped slot along the top thereof formed by an outwardly bent portion of the casing wall, a reciprocatory member adapted to be moved into and out of said slot to fasten a cover to the case, a cover, means on said cover consisting of a bolt to support said member and actuate it, an arm carried by said bolt adapted to engage with shoulders on said reciprocatory member for the actuation thereof, said bolt passing through a slot in said reciprocatory member, and a resilient washer beneath said cover around said bolt between it and said reciprocatory member.

8. In combination, a case having a marginal U-shaped slot along the top thereof formed by an outwardly bent portion of the casing wall, a reciprocatory member adapted to be moved into and out of said slot to lock a cover to the case, a cover, means on said cover consisting of a bolt to support said member and actuate it, an arm carried by said bolt adapted to engage with shoulders on said reciprocatory member for the actuation thereof, said bolt passing through a slot in said reciprocatory member, and a resilient washer beneath said cover around said bolt

between it and said reciprocatory member, and a metallic washer between the resilient washer and said reciprocatory member.

9. In combination, a case having a marginal **U**-shaped slot along the top thereof formed by an outwardly bent portion of the casing wall, a reciprocatory member adapted to be moved into and out of said slot to fasten a cover to the case, a cover, means on said cover consisting of a bolt to support said member and actuate it, an arm carried by said bolt adapted to engage with shoulders on said reciprocatory member for the actuation thereof, said bolt passing through a slot in said reciprocatory member, and a resilient washer beneath said cover around said bolt between it and said reciprocatory member, and a metallic washer between the resilient washer and said reciprocatory member, and a yielding member between said cover and the upper margin of the case to seal the joint therebetween.

10. In combination, a case having a marginal **U**-shaped slot along the top thereof formed by an outwardly bent portion of the casing wall, a reciprocatory member adapted to be moved into and out of said slot to fasten a cover to the case, a cover, means on said cover consisting of a bolt to support said member and actuate it, an arm carried by said bolt adapted to engage with shoulders on said reciprocatory member for the actuation thereof, said bolt passing through a slot in said reciprocatory member, and a resilient washer beneath said cover around said bolt between it and said reciprocatory member, and a metallic washer between the resilient washer and said reciprocatory member, and a yielding member between said cover and the upper margin of the case to seal the

joint therebetween, and a depending flange on the cover extending over the exterior of the **U**-shaped portion of the case and closely adjacent thereto.

11. In a container, a case having an overhanging horizontally disposed **U**-shaped portion on the upper margin thereof, a resilient washer mounted on the upper side thereof and a cover adapted to have its margin rest on said washer, and a depending marginal flange disposed along the outermost portion of the case closely adjacent thereto.

12. A case, a cover, a resilient seal therebetween, a reciprocating fastening means adapted to be inserted within a cavity in the case to lock the cover and case, actuating means to actuate said reciprocating means, a bolt for actuating the actuating means and supporting it threaded through said actuating means and adapted to draw the cover down on the case, compressing the resilient seal.

13. A case having means to receive a fastening member, a cover, a resilient seal, a reciprocating fastening member guided by and supported by the case, a bolt carried by the cover, a finger on said bolt adapted to move the fastening member into and out of engagement with the case, said finger being threaded on said bolt adapted to be turned by it, said parts being so arranged that as the bolt is turned it will draw the cover down on the case and form an air-tight and water-tight seal with the case, cover and resilient member.

In testimony whereof, we affix our signatures.

RALPH E. SMITH.
